FRED M. MILLER, OF BALA, PENNSYLVANIA

CHECKER BRICK MOLDING MACHINE

Application filed March 7, 1931. Serial No. 520,860.

My device is an improved machine for making bricks or similar objects of clay or like material and is particularly adapted for the rapid and economical production of perforated bricks of refractory material for use as "checkers" in blast furnaces, gas manufacturing apparatus or the like.

My machine consists of means for extruding clay, a die through which the clay may be extruded, a mold box, means for supporting the mold box so that it may be revolved about a horizontal axis, means for cutting off the finished brick in the mold box, an off bearing table having pins projecting into said mold box, fastening means for attaching said mold box to said die, fastening means for attaching said off bearing table to said mold box, and means for raising or lowering said off bearing table and for raising and lowering said mold box on said off bearing table.

For a further exposition of my invention reference may be had to the annexed drawings and specification at the end whereof my invention will be specifically pointed out and claimed.

In the drawings,

Figure 1 is a side elevation of parts of my device with parts shown in vertical cross section.

Figure 2 is a side elevation of the die, cutting means and mold box taken at right angles to Figure 1.

Figure 3 is a cross section on line 3-3 of Figure 1 in the direction of the arrows.

Figure 4 is a side elevation of the die, mold box and off bearing table with parts shown in vertical cross section.

Figure 5 is a plan view of the mold box and off bearing table with parts shown in horizontal cross section.

Figure 6 is a plan view of one form of brick which can be made in my device.

Figure 7 is a vertical cross section on line 7-7 of Figure 6.

In the embodiment of my invention chosen for illustration in the drawings, my device is shown as consisting of means for extruding clay. This means is shown as consisting of an extrusion head 1 but this may be a screw

conveyor or other device suitable for the purpose. The extrusion means 1 are operated by a source of power 2 which is shown in this instance as consisting of a steam piston and cylinder but which may be an hydraulic press, an electric motor or any other convenient source of power.

My machine includes a hopper 3 which is adapted to receive clay for making bricks. Hopper 3 has thereon a pipe 4 from which perforations 5 lead into the hopper 3 for the purpose of supplying oil to the hopper. Hopper 3 connects at its lower end with a cylinder 6 into which extrusion head 1 fits. At its lower end cylinder 6 is provided with a die generally indicated at 7 which may be of the double shape shown in the drawings or which may consist of but a single nozzle-like member of somewhat smaller cross section than cylinder 6. On die 7 are located pins 8 which serve as guides for the mold box. The mold box is generally indicated at 9 and has in its upper face holes 10 which receive pins 8 therein and which thereby guide mold box 9 into proper position beneath die 7. Mold box 9 also carries trunnions 11 which slide in slots 12 in guides 13 and which provide means for guiding and supporting mold box 9. One of the trunnions 11 carries a handle 14 which provides a means for rotating the mold box 9 about a horizontal axis. In its lower surface, mold box 9 is provided with tapered orifices 15. Mounted beneath mold box 9 is an off bearing table generally indicated at 16 which carries a plurality of pins 17 thereon, pins 17 being aligned with the orifices 15 and being adapted to pass therethrough. The bearing table 16 is mounted on a standard 18 which is provided with means for raising or lowering the off bearing table. These means consist of a clamp 19 attached to standard 18, a plurality of ropes 20 attached to said clamp, counterweight 21 attached to said ropes and a hand wheel 22 operatively connected to one of said ropes.

Referring more particularly to Figures 2 and 3 there are shown attached to die 7 cutting means for separating the finished brick in mold box 9 from the clay in die 7. These

means may consist of a wire 23 mounted in a bow 24 which in turn is pivotally mounted on a support 25 which is shown as attached to die 7.

5 Having reference now especially to Figures 4 and 5, the die 7 is shown as having a plurality of lugs 26 thereon which are adapted to cooperate with a plurality of clamping levers 27 which are pivotally mounted on 10 mold box 9. These elements serve to attach mold box 9 to die 7. As is best seen in Figure 5 mold box 9 may be composed of a plurality of parts marked 9a, 9b and 9c in Figure 5. These parts are attached together by 15 means which permit the expansion of mold 9 about the brick which has been formed therein. These expansion means consist of a plurality of screws 28 which have shou- 20 dered portions 29 thereon. The said shou- dered portions bear on lugs on the respective mold portions 9a, 9b and 9c. Screws 28 also have screw threaded portions 30 with which are adapted to contact nuts 31 which bear against the lugs on adjacent mold sections 25 9b, 9c and 9a. Screws 28 are also provided with handles 32 which are clamped or otherwise suitably attached to the screws and which serve as means for imparting a rotary motion to the screws. Adjacent the lower 30 edge, the mold box 9 is provided with a plurality of lugs 33 which serve to cooperate with clamping levers 34, the latter being pivotally mounted on off bearing table 16.

As noted above, off bearing table 16 is provided with a plurality of pins 17 attached thereto in any convenient manner. Pins 17 are provided at their upper ends with caps 35 which are attached to the pins 17 by screws 36 or in any other convenient manner.

40 Figures 6 and 7 show a brick 37 having a plurality of perforations 38 therein which may be conveniently made in my machine.

The operation of my machine is as follows: Starting from the position shown in Figure

45 1 the off bearing table 16 is lifted by means of hand wheel 22 so that the pins 17 pass through the orifices 15 and the mold 9 is lifted by the off bearing table 16. During this lifting operation the mold 9 is guided by 50 means of trunnions 11 in slots 12 in elements 13. Upon further lifting of off bearing table 16 and mold 9, guide pins 8 enter holes 10 so that mold 9 is correctly located with reference to die 7. Clamping levers 27 are then 55 attached to lugs 26 so that mold 9 is fastened to die 7 and clamping levers 34 are attached to lugs 33 so that the off bearing table is firmly attached to mold 9. Hopper 3 and cylinder 6 have previously been filled with clay. 60 Steam is then let into cylinder 2 so that extrusion head 1 is forced into cylinder 6 and clay is forced out of die 7 into mold box 9. The interior diameter of mold box 9 may be conveniently made slightly greater than the interior diameter of die 7 so that there are no

projecting shoulders preventing the clay from entering the mold box and so that the lubricating oil which is supplied to the clay and cylinder 6 by means of pipe 4 and holes 5 may flow down from die 7 into mold box 9. 70 Steam is permitted to pass into cylinder 2 until a suitable predetermined pressure is registered on a steam gauge (not shown because it is a standard article not forming a part of the invention) attached to cylinder 2. 75 If other extruding means are used their operation is continued until mold box 9 is filled with clay. The extrusion head 1 may then be lifted and the mold box 9 unclamped from the die 7. Cutting wire 23 is then actuated 80 between die 7 and mold box 9 and severs the clay in the mold box 9 from the clay in die 7. Off bearing table 16 and mold 9, which is carried thereby, are then dropped until mold 9 is supported by the bottom of slots 12 upon 85 trunnions 11. The excess clay is then removed from the top of the clay in mold box 9 and the surface of the brick therein is "slicked" by hand. Off bearing table 16 is then further lowered thereby drawing pins 90 17 out of mold box 9 and out of the clay therein. A pallet or wooden board is then placed on top of pins 17. Mold box 9 is then inverted by revolving the mold box about the horizontal axis by means of handle 14. Off bearing 95 table 16 is then elevated until the pallet rests against the lower surface of the brick in mold box 9. The mold box 9 is then expanded by loosening screws 28 by means of handles 32. This frees the brick 37 from the mold box 9. 100 Off bearing table 16 is then lowered carrying the brick out of mold box 9. The cycle of operation is then repeated to form another brick.

I do not intend to be limited in the practice of my invention save as the scope of the prior art and of the attached claims may require.

I claim:

1. A molding machine including a cylinder, means for extruding the clay from said cylinder, a die forming an outlet for clay from said cylinder, a mold box movably mounted for vertical movement with respect to said die and rotatable about a horizontal axis, and an off bearing table mounted for vertical movement and located to carry said mold box into position adjacent said die. 110

2. A molding machine including in combination a cylinder, means for extruding clay from said cylinder, a die forming an outlet for clay from said cylinder, a mold box movably mounted for vertical movement with respect to said die and rotatable about a horizontal axis, an off bearing table mounted for vertical movement to carry said mold box into position adjacent said die, and means for severing clay in said mold box from clay in said die. 120

3. A molding machine including in combi- 125

nation a cylinder, means for extruding clay from said cylinder, a die forming an outlet for clay from said cylinder, a mold box mounted for movement relative to said die and rotatable about a horizontal axis, an off bearing table mounted for movement relative to said mold box and for movement carrying said mold box into position adjacent said die, means for fastening said mold box to said die, and means for fastening said off bearing table to said mold box.

4. A molding machine including in combination, a cylinder, means for extruding clay from said cylinder, a die forming an outlet for clay from said cylinder, a mold box mounted for movement relative to said die and rotatable about a horizontal axis, an off bearing table mounted for movement relative to said mold box and for movement for carrying said mold box into position adjacent said die, and means for expanding said mold box.

5. A molding machine including in combination a cylinder, means for extruding clay from said cylinder, a die forming an outlet for clay from said cylinder, a mold box mounted for movement relative to said die, and rotatable about a horizontal axis, an off bearing table mounted for movement relative to said mold box and for movement to carry said mold box into position adjacent said die, and pins on said off bearing table projecting into said mold box when said mold box and said off bearing table are adjacent.

6. A molding machine including in combination a cylinder, means for extruding clay from said cylinder, a die forming an outlet for clay from said cylinder, means for lubricating clay in said machine, a mold box mounted for movement relative to said die, means for rotating said mold box about a horizontal axis, and an off bearing table mounted for movement relative to said mold box and for movement carrying said mold box into position adjacent said die.

7. A machine for molding checkerbrick including in combination means for extruding clay through a die, an open top rollover mold box having a perforated bottom, guides for permitting relative movement of the box and die and for permitting the box to roll over, a table provided with pins adapted to pass through the perforations in the bottom of the box, means for moving said table for inserting the pins into the box and for putting the box into clay receiving position and for putting the box into rollover position and for withdrawing the pins into pallet and brick receiving position when the mold is rolled over, means for cutting off clay between the die and the mold, and means for expanding the mold.

8. In a brick molding machine the combination of a rollover mold box open at the

top and having perforations in the bottom, means for filling the box, pins adapted to enter and recede from the interior of the box through said perforations, and means for moving the pins into pallet and brick receiving position when the mold is rolled over.
